By his Attorney, George Beeler

UNITED STATES PATENT OFFICE.

JOSEPH GILLEN, OF FLUSHING, NEW YORK.

COMBINED CURB BOX AND AUTOMATIC GAS CUT-OFF.

Application filed February 5, 1923. Serial No. 616,998.

To all whom it may concern:

Be it known that I, JOSEPH GILLEN, a citizen of the United States, residing at Flushing, in the county of Queens and State 5 of New York, have invented certain new and useful Improvements in Combined Curb Boxes and Automatic Gas Cut-Offs, of which the following is a specification.

This invention relates to cut off mechanism for gas supply apparatus and has particular reference to that type of devices covered by Letters Patent of the United States No. 1172,977, and over which this is an improvement.

15 Among the direct objects of the present construction is to provide a combination quick acting or automatic cut off and curb box, whereby the action of the cut off at the curb box is rendered not only quick and easy but always certain, taking into account that in many cases the cut off means at the curb box, by reason of rust or other weather conditions, is frequently not only inaccessible but impossible of operation.

25 Another object of the invention is to provide a cut off operative remote from the building and in the region of the curb box or point beneath the curb box, and which may be caused to operate either automatically or by hand action of any one in authority such as a fireman or employee of the gas company and from different positions or places with respect to the cut off valve.

35 A still further object is to provide an automatic cut off between the outside of the building and the gas main, operative automatically as a result of a fire or excessive heat within the building.

40 With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same 45 parts in the several views, and in which—

50 Figure 1 is a vertical sectional view indicating diagrammatically the general relationship between the street main, the sidewalk and curb box, and the front wall of the building, with my improvements in position.

Fig. 2 is a vertical transverse section on the line 2—2 of Fig. 1.

Fig. 3 is a similar detail on the line 3—3 of Fig. 1.

Referring now more specifically to the drawings, I indicate at C the curb extending along the street S beneath which is the main M and remote from the outer wall 10 of the building within the basement of which is 65 the meter 11 to which leads the branch pipe 12 from the main.

13 indicates the curb box having a cover 14 usually flush with the sidewalk and from which the cut off valve is ordinarily accessible. The valve comprises a casing 15 interposed in the pipe 12, said casing being shown as of cylindrical form and with a hemispherical closed bottom. Between the lid 16 of the casing and the bottom of the 70 curb box 13 is a rigid casing 17 preferably of the nature of an inch gas pipe, the same being connected firmly and hermetically to the aforesaid box and casing.

75 The cut off valve 18 is designed to conform 80 to the inner surface of the casing 15, having a cylindrical body and a hemispherical lower end, but shorter in length than the casing, so that while the valve is held normally elevated as illustrated there is clear 85 passage between the members of the pipe 12 on opposite sides of the casing. Connected to the top of the valve and extending thence upward through the casing 17 is a rod or stem 19 to which is secured or formed a 90 collar 20 not far below the bottom of the curb box 13. The upper portion of the stem 19 is fitted slidably through a packing gland 21 at any convenient place as within the box 13 and through which leakage of gas upward through the casing or leakage of moisture downward are prevented. A coil spring 95 22 of sufficient strength surrounds the stem between the collar and the gland 21, the same being normally under compression and which therefore tends to throw the valve 100 downward for closing the valve.

105 Formed on or secured to the upper end of the stem 19 is a handle or head 23 of any suitable design or shape but indicated as in the form of a T-head with a part extending horizontally below the cover 14 of the box.

110 Any suitable means may be provided, preferably in co-operation with the head 23, for holding the valve in normal elevated position. To this end I provide a strut 24 whose lower end is seated in a seat or

pit 25 formed in the bottom of the box 13 and whose upper end co-operates as by means of an anti-friction roller 26 with the head 23 after the head and valve are drawn 5 upward by hand. To release the head and valve the operator may lift the cover 14 and reaching directly into the box may displace the strut either by hand or the use of a single tool, thereby allowing the spring to 10 throw the valve downward, the head 23 at this time approaching the bottom of the box.

For the operation or manipulation of the cut off valve from a distance I provide a 15 cable 27 attached at 28 to the strut and extending thence laterally beneath the sidewalk preferably into or through the building. As shown this cable leads through a 20 closed guide way 29 extending through the basement wall 10' and having on its inner end a housing 30 which may be provided if desired with anti-friction rollers 31. The inner end 27' of this cable is secured at some elevated point as upon a hook 32, and 25 interposed in the cable below the hook is a fusible link 33. A weight W is suspended from the cable beneath the link as at the point 34 and above the guide rollers 31. An auxiliary line or cable 35 is attached to the main cable adjacent to the rollers 31 and leads upward through a guide way 36 and thence outward through the wall 10 to a handle or ring 37 accessible from the 30 outside of the building, especially for use by a fireman. Access to this handle 37 is normally closed by a plate of glass 38 which of course is easily breakable in an emergency.

The operation of this device constructed as just above described is somewhat as follows: In case of a fire in the building, the 40 link 33 which is ordinarily composed of a metal having a low fusing point, will melt and so part the cable 27, 27' and allow the weight to gravitate and pull the cable over the lower guide roller and along the guide 45 29 and pull the strut 24 from normal position, allowing the head 23 to drop as above described. Sufficient slack may be observed in the auxiliary cable 35 to permit this automatic result. Again, irrespective of the 50 presence of fire within the building adjacent to the mechanism just described a fireman,

for example, by pulling outward upon the handle 37 may withdraw the strut from holding position and so close the valve 18. 55 The location of the point of attachment 34 above the guide rollers 31 will afford ample movement of the cable in this manner without requiring the fireman to lift the weight W. Any portion or all of the curb box and tubular casing 17 may be filled or supplied with grease for maintaining the parts in freely movable condition. 60

I claim:

1. The combination with a gas supply 65 pipe, a cut off valve therein, and a curb box remote from the outside of the building inclosing valve actuating means normally held in inoperative position, of means operable from the inside of the building to 70 release the valve actuating means to effect the closing of the valve in the cut off.

2. Mechanism as set forth in claim 1 in which the operable means for effecting the 75 closure of the valve is automatic as a result of abnormal heat within the building.

3. Mechanism as set forth in claim 1 and additional means for effecting the closing 80 of the valve comprising a manually operated member accessible at the outside of the building.

4. In a device of the character set forth, the combination of a curb box, a gas supply pipe, a cut off valve located in the supply pipe beneath the curb box, a hermetically sealed casing extending between the curb box and the valve casing, a valve stem 85 slideable in said casing and having a head within the curb box, and means co-operating with the head for holding the valve normally open.

5. Mechanism as set forth in claim 4 in which the means co-operating with the head is a rigid strut displaceable directly by hand within the curb box. 95

6. Mechanism as set forth in claim 4 in which the means co-operating with the head is a rigid strut and a flexible member extending laterally from said strut to a point within the building. 100

In testimony whereof I affix my signature.

JOSEPH GILLEN.
